UNITED STATES PATENT OFFICE.

JOHN H. THORN, OF YOUNGSTOWN, OHIO.

LIQUOR-PUMP.

SPECIFICATION forming part of Letters Patent No. 332,171, dated December 8, 1885.

Application filed November 28, 1884. Serial No. 149,000. (No model.)

To all whom it may concern:

Be it known that I, JOHN H. THORN, a citizen of the United States, residing at Youngstown, in the county of Mahoning and State 5 of Ohio, have invented certain new and useful Improvements in Liquor-Pumps; and I do hereby declare the following to be a full, clear, and exact description of my invention, such as will enable others skilled in the art 10 to which it appertains to make and use the same, reference being had to the accompanying drawings, which form part of this specification.

This invention relates to certain improvements in liquor-pumps; and it has for its objects, to provide a pump that may be securely fastened in the bung-hole of the barrel at any desired height, and which may be conveniently manipulated when so secured, as more 15 fully hereinafter specified. These objects I attain by the means illustrated in the accompanying drawings, in which—

Figure 1 represents a view, partly in side elevation and partly in section, of my improved pump. Fig. 2 represents a detached view of the valve-lifting attachment. Fig. 3 represents a view of the piston and a portion of the piston-rod; Fig. 4, a perspective view of the valve employed in connection with 20 the pump; and Fig. 5, a horizontal sectional view of the filter-section, taken on the line $x-x$ of Fig. 1.

The letter A indicates the pump barrel or cylinder, which is constructed of metal or other suitable material, and is provided with the usual discharge-pipe near the top.

The letter B indicates a device by which the pump is clamped and supported in the bung-hole. This device consists of two split 25 rings, a, b , joined by a series of beveled wings, c , which widen from their lower to their upper ends, as clearly indicated in the drawings. The pump-barrel passes through these rings, and when in place the device is intended to remain permanently upon the pump, 30 forming part of the same. The lower end of the pump-barrel is provided with a short tubular section, C, which is externally screw-threaded at both ends, one end being secured 35 into the pump-barrel, and the other end being for the attachment of the filter-section D. The section C is provided with a valve-seat on its top for the valve E, which is fluted, as

shown in Fig. 4, and is provided with a shoulder, F, to fit the seat and insure a tight joint. 55 The said valve E is constructed of vulcanized rubber or other light material which will float, so that after one or two strokes of the pump-piston the pump will act as a siphon.

The letter G indicates the piston, which is 60 attached to a piston-rod, H, the said rod extending through a stuffing-box at the top of the pump. The piston is provided with a valve, I, adapted to be lifted and held by the upward current of the liquid when the pump 65 is used as a siphon.

The letter D, as above indicated, represents the filter-section, which is tubular in shape, and which may be packed with any suitable material. The said section is 70 perforated, as shown in Figs. 1 and 5, to permit the entrance of the liquid.

The letter K indicates a detachable section, which is slotted, as indicated by k , and which has located within it a rod, l , from which 75 projects a pin, m , through the slot. The upper end of said section is screw-threaded, so that it may be screwed into the filtering-section before mentioned.

The operation of my invention is as follows: 80 The pump is inserted in the bung-hole and the clamping device entered around it. When inserted to the proper depth, the clamping device is driven or forced into the bung-hole, so as to clamp the rings around the pump-barrel 85 and hold it securely. The pump is then ready for operation in the usual manner.

When the pump is removed from the barrel, any remaining liquor may be discharged by raising the rod b , which lifts the valve above it. 90

Having thus described my invention, what I claim, and desire to secure by Letters Patent, is—

The combination, with the pump-barrel, of the clamping-bung consisting of two rings 95 connected by tapering wings split at one side, so as to clamp the tube in any desired position when inserted in the bung, substantially as specified.

In testimony whereof I have affixed my signature in the presence of two witnesses.

JOHN H. THORN.
